HOOK FOR ROCK AND MOUNTAIN CLIMBING

William A. Feuerer, 20009½ Oak St.,
Santa Monica, Calif. 90405

Filed Oct. 10, 1968, Ser. No. 13,933

Term of patent 14 years

Int. Cl. D8—03

U.S. Cl. D8—230

FIGURE 1 is a perspective view of a hook for rock and mountain climbing, showing my new design;

I claim:

The ornamental design for a hook for rock and mountain climbing, substantially as shown.
